ATTORNEYS.

UNITED STATES PATENT OFFICE.

JACOB FRYSINGER, OF MILAN, ILLINOIS.

RAILROAD-RAIL TIE AND FASTENING.

SPECIFICATION forming part of Letters Patent No. 400,558, dated April 2, 1889.

Application filed June 25, 1888. Serial No. 278,189. (No model.)

To all whom it may concern:

Be it known that I, JACOB FRYSINGER, of Milan, in the county of Rock Island and State of Illinois, have invented a new and useful

5 Improvement in Railroad-Rail Ties and Fastenings, of which the following is a specification.

This invention contemplates certain improvements in railroad-rail ties and fastenings, having for its object, mainly, to provide for holding the stringers against lateral displacement—moving toward each other or spreading apart—while provision is also made to permit of the ready removal of a worn-out 10 tie and its replacement by a new one, and to effect the expeditious laying or putting down of the track; and to these ends the nature of the invention consists of a tie formed of upper and lower bars and an intermediate bar 15 interposed between and edgewise to the aforesaid bars and endwise to the sleepers, and of certain details of construction, substantially as hereinafter more fully described and claimed.

20 25 In the accompanying drawings, Figure 1 is a transverse section of my improved railroad-rail tie and fastening; and Figs. 2 and 3 are also sectional views of the same, taken on the lines 2 2 and 3 3, respectively.

30 35 In carrying out my invention I take three flat or plate-like bars, A A A', to form the tie. The upper and lower bars, A A, are arranged one below the stringers a a and the other above, and is received in transverse grooves or recesses b b in the upper surfaces 40 45 of the stringers. The grooves or recesses b b effect the holding of the tie and stringers in their relative positions. Through the bars A A and the stringers are passed screw-bolts c c, securing the same together. The other or intermediate plate-like bar, A', is disposed edgewise between and let into shallow channels or grooves d d in the upper and lower plate-like bars, A A, and between the 50 55 stringers a a. The plate A' itself is thus retained in its edgewise position and against lateral displacement, while the stringers are also held against lateral displacement, the plate A' immediately preventing the inward lateral movement of the stringers, while the plates A prevent their outward lateral movement. The rail-chairs are formed of clamp-plates e e, resting upon the upper one of the plate-like bars A and the flanges of the rails, 55 the same bolts, c c, as connect together the

said bars and stringers, passing through said clamp-plates or chairs and fitted with nuts, thus securing the tie, stringers, rails, and chairs all together in a simple and expeditious manner.

60 From the foregoing it will also be seen that when it is desired to renew a worn-out part or parts it is only necessary to remove the nuts of the screw-bolts and lift the upper plate-like bar out of the grooves or recesses 65 of the stringers, which will permit the removal of the defective part or parts and the replacement thereof by a sound or new part or parts, as the case may be; also, the several parts of the track, formed as above described, 70 75 are readily and easily handled, enabling the expeditious putting down or laying of the track.

The stringers may be made either of wood or metal.

75 Having thus fully described my invention, what I claim, and desire to secure by Letters Patent, is—

1. The railroad-rail tie-fastening consisting of the upper and lower bars and an intermediate bar interposed between and edgewise to the aforesaid bars and endwise to the sleepers, substantially as set forth.

2. The railroad-rail tie consisting of the upper and lower plate-like bars and an intermediate edgewise-disposed plate-like bar let into grooves or channels in the aforesaid bars, substantially as set forth.

3. The railroad-rail tie consisting of the upper and lower plate-like bars and an intermediate edgewise-disposed plate-like bar let into grooves or channels in the upper and lower bars, the upper and lower bars being arranged one above and let into transverse grooves or recesses in the upper surfaces of 90 the stringers, and the lower one below the stringers, substantially as specified.

4. The railroad-rail tie comprising the upper and lower plate-like bars and an intermediate edgewise-disposed plate-like bar let into grooves or channels of the upper and lower bars, and the chairs consisting of clamp-plates resting upon the upper bar and held in place by bolts passing through said upper and lower bars, substantially as set forth.

JACOB FRYSINGER.
